UNITED STATES PATENT OFFICE.

ALFONS MAUSER, OF COLOGNE-MARIENBURG, GERMANY.

CLOSURE FOR VESSELS.

Application filed November 6, 1924, Serial No. 748,032, and in Germany March 30, 1924.

My invention relates to closures for vessels and particularly for metal receptacles and has especial reference to that type of closure in which there is employed a locking ring 5 consisting of an angular piece of arched or circular form engaging the marginal portion of the cover proper. Such locking ring is adapted to press with a wedge-like action against the cover and against an annular 10 abutment located at the edge portion of the receptacle at a certain distance from the cover.

My present invention has for its object to improve closures of the character indicated 15 above and to provide a very efficient novel construction of this type including means for supporting and holding the locking ring in its locking position and for also securing a packing or gasket in position and for preventing spreading or displacement of said 20 packing.

Four different forms of my invention are illustrated in the accompanying drawings as examples of the many forms in which my invention may be embodied. Fig. 1 is a plan view, partly in section, of one form of my 25 invention; Fig. 2 is a section on line 2—2 of Fig. 1, and Figs. 3, 4, and 5 are fragmentary sectional views illustrating three other 30 forms of my invention.

The receptacle A, which may be of any conventional or special shape, is constructed of suitable material, such as sheet metal and has its side wall 10 connected by means of 35 a lapped or folded joint 11 with a cover seating ring 12. In the form shown in Figs. 1 and 2, the cover seating ring is constructed of sheet metal bent to form a step-like cross-section having a higher supporting surface 40 13 and a lower supporting surface 14, which surfaces serve respectively for supporting a locking ring and a packing presently to be described. An outer ring 15 which encases the joint 11 extends over the higher surface 45 13 and has a portion of its upper horizontally extending flange 16 spaced therefrom to provide a channel 17 in which a portion of the locking ring is adapted to be inserted.

The locking ring 18 is constructed of 50 sheet metal and consists of a plane horizontally extending flange 19 adapted to be secured in the channel 17 and a cylindrical flange 20 extending downwardly from said horizontal flange at the inner edge thereof.

55 The locking ring is split as indicated at 21

in Fig. 1 to permit it to be gradually inserted in position and also to provide it with the required resiliency; it being understood that the diameter of the ring is so proportioned that when not in position upon the receptacle, the split ends thereof will spread and cause the ring to assume a larger diameter than when it is locked in position upon the receptacle.

The cover 22 of the receptacle is formed 60 with a raised marginal portion, which in the constructional example illustrated, consists of an upwardly extending cylindrical flange 23 having at its upper edge a horizontal marginal flange 24. An annular recess 25 is formed at the base of the cylindrical flange 23 to receive the lower end of the cylindrical flange 20 of the locking ring 18; the inner wall 25^a of the said recess forming an abutment to prevent inward radial 70 movement of the locking ring to an extent which would permit disengagement thereof from the channel 17.

A packing 26 of any suitable material and preferably of annular shape is adapted to 80 be seated upon the lower surface 14 of the cover seating ring; when the parts of the closure are assembled, the packing is confined in a vertical direction between the marginal flange 24 of the cover and the lower surface 14 of the cover seating ring, while spreading of the packing in a horizontal direction is prevented by the vertical cylindrical flange 23 of the cover and the upwardly extending wall 27 of the cover seating ring. 90

In assembling the closure, the packing is placed upon the lower surface 14, after which the cover 22 is placed in position, with the marginal flange 24 thereof upon the packing. The locking ring 18 is then 95 placed in its position with its flanges 19 and 20 engaged within the channels 17 and 25 respectively. In inserting the locking ring, one end of the flange 19 is inserted within the channel 17 and the ring is forced gradually into position therein by the use of a suitable tool; the tool being moved around the circumference of the ring until the other end thereof snaps into locked position. In order to facilitate the insertion of the locking ring, the vertical flange 20 thereof is cut away a short distance from the split ends. For convenience in removing the ring, a slot 28 is cut into the horizontal flange 19 adjacent to one of the ends of the 100 110

ring, said slot extending inwardly from the outer edge of the ring a sufficient distance for the inner edge of the slot to be exposed beyond the flange 16 to permit the insertion of a tool for springing the ring inwardly to unlock it.

The construction illustrated by Fig. 3 is of the same general character as the one described with reference to Figs. 1 and 2, 10 the difference being chiefly in the shape of the cover seating ring 12^a which is shown as provided with an annular upwardly projecting ridge 27^a provided for the purpose of stiffening said ring and for cooperating 15 with the vertical flange 23 of the cover to prevent spreading of the packing. The upper face 13^a of the ridge 27^a corresponds to the upper supporting surface 13 of the cover seating ring shown in Fig. 2; said 20 face cooperating with the flange 16^a of the outer ring 15^a to define a channel corresponding to the channel 17, in which the horizontal flange 19 of the locking ring engages, and the lower surface 14^a serving as 25 a support for the packing 26.

While in Figs. 1, 2, and 3, the cover seating ring is located within the mouth of the receptacle, Figs. 4 and 5 illustrate constructions in which such seating ring is disposed 30 exteriorly of the receptacle and surrounds the same at the mouth. In Fig. 4 the cover seating ring 12^b is of angular cross-section, having a vertical cylindrical member 27^b on the upper face 13^b of which the horizontal 35 flange 19 of the locking ring is seated; the face 13^b cooperating with the flange 16^b provided at the upper end of the outer ring 15^b to define the channel 17^b in which the flange 19 engages. The side wall 10 of the 40 receptacle engages with the inner circumference of the cover seating ring instead of forming a lapped joint with the outer part of said ring, as shown in Figs. 2 and 3. In other respects the construction is substantially 45 the same as in Figs. 2 and 3. Instead of the angular formation of the cover seating ring shown in Fig. 4, I may employ a ring having a U-shaped or semi-circular cross-sectional profile.

50 In Fig. 5 a one part cover seating ring 12^c of suitable profile is employed which is illustrated as a massive body of considerable thickness, which is true also of the cover seating ring 12^b of Fig. 4, although I might, 55 instead of this, in both instances, employ a ring made of sheet metal. If desired, an outer ring such as indicated by the reference character 15^c may be added in order to increase the security of the closure. In 60 this form, the channel 17^c, for the accommodation of the flange 19 of the locking ring is formed entirely in the cover seating ring 12^c.

In order that the side wall 10 of the receptacle may be connected with the cover

seat ring in such a manner as to prevent relative movement of these parts, I may, as indicated in Figs. 4 and 5, cause the extreme edge 11^b of the said side wall 10 to project into a suitable groove of the said ring. Such a connection or fastening may be considered the equivalent of one obtained by screws, bolts, interlocking projections, and recesses or of one obtained by electric welding.

70

75

In each of the forms of my invention illustrated, the locking ring is identical, being constructed of sheet metal and split as indicated at 21 in Fig. 1 to enable it to be sprung into locked position, said ring possessing an inherent resiliency tending to expand the same and cause it to hold itself securely in said locked position. It will be noted that in all forms of the invention, the outer edge of the horizontal flange 19 of the locking ring is supported upon a horizontally extending higher surface 13, 13^a, 13^b, etc. of the cover seating ring, which surface cooperates either with the flange 16 of the cover seating ring to define a channel in 90 which said flange 19 is engaged to prevent canting of the ring, or said channel is formed directly in the ring as indicated by the reference character 17^c in Fig. 5.

90

While I have shown these higher surfaces 13, 13^a, 13^b, as continuous, it will be understood that an interrupted series of lugs or abutments would be the full equivalent. Likewise while the recess 25 of the cover has been shown as a continuous annular 100 groove, the substitution of a series of upwardly projecting lugs to form abutments for preventing inward movement of the locking ring would be the same in principle as the provision of the recess. It will also be noted that in all the examples of construction herein illustrated, I have resorted to the principle of confining the packing 26 between a pair of substantially vertically extending walls to prevent spreading of said 110 packing in a horizontal direction.

105

110

115

120

125

I claim:

1. A closure of the class described, comprising a cover having a raised marginal portion and an abutment spaced interiorly of said portion, a cover support located at the mouth of the receptacle and having a pair of horizontally extending, upwardly facing, annular supporting surfaces, arranged one above the other in stepped concentric relationship, packing interposed between the marginal portion of said cover and the lower of said surfaces, and a one-piece, resilient, split locking ring of angular cross section having an upper member engaging the higher of said surfaces, and a lower member extending into the space between said raised marginal portion and said abutment of the cover.

130

2. A closure of the class described, com-

prising a cover having an upwardly open annular groove, a cover support located at the mouth of the receptacle and having a pair of horizontally extending, upwardly facing, annular supporting surfaces, arranged one above the other in stepped concentric relationship, packing engaging the cover and the lower of said surfaces, and a one-piece, resilient, split locking ring of an annular cross section having an upper member engaging the higher of said surfaces, and a lower member extending into said annular groove of the cover.

3. A closure of the class described comprising a cover seat and a cover, said cover having a vertically extending flange, a horizontally extending marginal portion, and an abutment spaced from said vertical flange to define therewith a vertical channel, said cover seat having a pair of horizontally extending, upwardly facing, annular supporting surfaces, arranged one above the other in stepped concentric relationship, means permanently associated with said cover seat to form with the upper of said surfaces a horizontally extending annular channel and a one-piece, resilient, split locking ring having a vertical flange to engage within said vertical channel and a horizontal flange to engage within said horizontal channel.

4. A closure of the class described comprising a cover seat and a cover, said cover having a vertically extending flange, a horizontally extending marginal portion, and an abutment spaced from said vertical flange to define therewith a vertical channel, said cover seat having a pair of horizontally extending, upwardly facing, annular supporting surfaces, arranged one above the other in stepped concentric relationship, means permanently associated with said cover seat to form with the upper of said surfaces a horizontally extending annular channel and a split locking ring having a vertical flange to engage within said vertical channel and a horizontal flange to engage within said horizontal channel, said locking ring being of resilient material and constructed and arranged to be sprung into engagement within said channels.

5. A closure of the class described comprising a cover seat and a cover, said cover having a vertically extending flange, a horizontally extending marginal portion and an abutment spaced from said vertical flange to define therewith a vertical channel, said cover seat having a pair of horizontally extending, upwardly facing, annular supporting surfaces, arranged one above the other in stepped concentric relationship, means permanently associated with said cover seat to form with the upper of said surfaces a horizontally extending annular channel and

a locking ring having a vertical flange to engage within said vertical channel and a horizontal flange to engage within said horizontal channel, the flanges of said cover and the lower surface of said cover seat cooperating to form an annular chamber, and a packing contained within said chamber.

6. A closure of the class described comprising a cover seat and a cover, said cover having a vertically extending flange, a horizontally extending marginal portion, and an abutment spaced from said vertical flange to define therewith a vertical channel, a horizontal inwardly extending flange permanently associated with said cover seat and a locking ring having a vertical flange to engage within said vertical channel and a horizontal flange to engage with said first named horizontal flange.

7. A closure for sheet metal receptacles comprising a cover seat having a pair of annular, horizontally extending, upwardly facing, supporting surfaces arranged in stepped concentric relationship with a vertically extending surface connecting them, a cover having an annular vertical flange and an annular marginal flange projecting outwardly from said vertical flange, said vertical flange being adapted to fit within the inner periphery of the lower of said pair of surfaces, the lower horizontal surface and the vertical surface of said cover seat, and the flanges of said cover forming the walls of an annular chamber, a packing mounted on the lower of said surfaces between the walls of said chamber, means permanently associated with the upper of said surfaces to define therewith an inwardly open horizontal channel, and locking means engaged within said channel and with said horizontal flange of said cover to hold said cover securely in engagement with said packing and within said cover seat.

8. In a barrel, drum, or the like container, having a mouth, a cover for said mouth, a cover support fixed to the container adjacent said mouth, a cover-retaining member engaging said support and said cover, and an annular securing member engaging said cover-retaining member to prevent vertical movement thereof.

9. A barrel, drum, or the like container, comprising a sheet-metal body portion with an opening at one end thereof, a cover adapted to close said opening, a cover support fixed to said body portion adjacent said opening and adapted to support said cover in operative position, a resilient cover-retaining member engaging said support and said cover, and a securing member fixed to said body portion and engaging said cover-retaining member.

ALFONS MAUSER.
